(57) **CLAIM**

The ornamental design for a sock sorter as shown and described.

DESCRIPTION

FIG. 1 is a perspective view of a first embodiment of the sock sorter showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof;

FIG. 8 is a perspective view of the first embodiment with environmental elements;

FIG. 9 is a perspective view of a second embodiment of the sock sorter showing my new design;

FIG. 10 is a top plan view thereof;

FIG. 11 is a bottom plan view thereof;

FIG. 12 is a left side elevational view thereof;

FIG. 13 is a right side elevational view thereof;

FIG. 14 is a front elevational view thereof;

FIG. 15 is a rear elevational view thereof; and,

FIG. 16 is a perspective view of the second embodiment with environmental elements.

The portions shown in broken lines are environmental elements and form no part of the claimed design.

1 Claim, 12 Drawing Sheets
